VALVE CONSTRUCTION FOR GROUNDED
AVIATION TRAINERSSamuel Arthur Douglas, Union, N. Y., assignor to
Link Aviation, Inc., a corporation of New York

Application November 30, 1945, Serial No. 631,906

7 Claims. (Cl. 35—12)

1

This invention relates to grounded aviation trainers of the type disclosed in U. S. Patents 1,825,462 and 2,099,857, issued to Edwin A. Link. More particularly, this invention relates to an improved main valve construction for use in such trainers.

As disclosed in the two above mentioned patents, and as is well known to the prior art, trainers of the type being considered include four collapsible-expansible bellows connected to a suitable vacuum source, such as a turbine, and to the atmosphere through what may be termed the fuselage control valves. These valves are operated by the control stick (or control column) in the trainer in such a manner that when the control stick is moved ahead, the elevator valve is operated so that vacuum is admitted to the forward pitching bellows and atmosphere to the rear pitching bellows, resulting in a diving of the fuselage which is controlled by the bellows. On the other hand, a rearward movement of the control stick operates the elevator control valve so that vacuum is admitted to the rear pitching bellows and atmosphere to the front pitching bellows, resulting in the fuselage's assuming a climbing attitude. When the control stick is moved to the left of its neutral position, it operates the aileron valve which admits vacuum to the left banking bellows and atmosphere to the right banking bellows, causing the fuselage to bank to the left. On the other hand, a movement of the control stick to the right of its neutral position operates the aileron valve so that vacuum is admitted to the right banking bellows and atmosphere to the left banking bellows, resulting in a banking to the right of the fuselage.

At the same time trainers of the type being considered employ a double acting turning motor which is connected to the source of vacuum and to the atmosphere through a rudder valve which is controlled by the rudder pedals which are conventionally placed in these trainers. When the left rudder pedal is pressed forward, the rudder valve is operated to admit vacuum to one side of the turning motor and atmosphere to the other, resulting in a turning of the trainer towards the left. On the other hand, when the right rudder pedal is pressed forward the rudder valve is operated so that vacuum and atmosphere are introduced in the opposite sides of the turning motor, and the trainer is rotated toward the right.

Also, these trainers include auxiliary valve arrangements so that the fuselage will automatically bank in the direction of its turning, will automatically turn in the direction of its banking,

2

and so that the nose of the fuselage will automatically drop whenever the fuselage is turning—just as occurs in the case of a plane in actual flight.

It is a principal object of this invention to replace the main control valves as well as the auxiliary valves known to the prior art by a more compact valve assembly which may be easily manufactured, assembled and adjusted, and which will eliminate a large portion of the linkages used in the prior art trainers to operate the various valves in order that the proper effects may be achieved.

In general, this invention comprises four valve sections placed vertically one above and in contact with the adjacent sections, together with a plate which is movable in a single plane by the movements of the control stick in order to operate the adjacent valve sections so as to produce the basic climbing and diving movements in response to the control stick movements.

Then my invention also includes means for moving the top valve section relative to the plate which is controlled by the control stick in order that the pitching attitude of the fuselage may be made dependent upon the factor of assumed air speed.

The basic fuselage turning movements are accomplished by rotation of the lowermost valve section in response to movements of the rudder pedals, while the automatic bank with turn and nose down with turn movements are also initiated by the rotation of the lowermost rudder valve section. The automatic turn with bank action is introduced by the rotation of the section lying immediately above the rudder valve section, this section being referred to as the auxiliary valve section.

The section immediately above the auxiliary effect valve section comprises six radially formed chambers, two of which connect with the pitching bellows, two of which connect with the banking bellows and two of which connect with the turning motor. Vacuum and atmosphere are selectively admitted to the six radial chambers of the main valve section in accordance with the movements of the control stick which selectively opens and closes the ports in the uppermost valve section, and in accordance with the movements imparted to the auxiliary effect valve section and to the rudder valve section.

In order that the exact nature of this invention may be better understood, reference is made to the accompanying drawings, wherein

Fig. 1 is a general exterior view of trainers of the type being considered showing the fuselage,

pitching and banking bellows, the turning motors, turbine, desk and conventional flight recorder.

Fig. 2 is a perspective view showing the control stick, the location of the main valve assembly, the main universal joint, the stationary base, rotatable carriage, turning motors and the pitching and banking bellows.

Fig. 3 is an exploded sectional view of the main valve assembly with which this invention is primarily concerned.

Fig. 3A is a top view of the main valve section, showing the six circumferentially spaced chambers.

Fig. 3B is a top view of the auxiliary effect valve section.

Fig. 4 is a perspective view showing the linkage interconnecting the auxiliary effect valve section with the universal joint, and

Fig. 5 is a top view of the plate attached to the top of the attitude valve section, together with the means for moving this section in accordance with the instant assumed air speed.

General description

Referring now to Figs. 1 and 2, the normally stationary base of the trainer is designated 10 and comprises a plurality of beams suitably fixedly attached to one another, as by bolts. A plurality of rollers 11 are provided in order that the entire training unit with the exception of the desk 12 and its associated elements may be manually moved from position to position. However, during operation of the training device the base 10 remains stationary. Fixedly attached to the base members 10 is the main hub 13 in which the main spindle 14 is rotatably mounted. Affixed to the main spindle 14 for rotation therewith are the horizontal cross arms 15 and affixed to the outer end of each of these cross arms is the upper end of one of the depending members 16, the lower ends of which support the carriage 17. Carriage 17 in turn supports the forward pitching bellows 18, the rear pitching bellows 19, the left banking bellows 20 and the right banking bellows 21. The lower end of each of these four bellows is affixed to the carriage 17 while the upper end of each of these bellows is affixed to the floor or bottom side of the fuselage 22. Carriage 17 also supports the two schematically shown turning motors 23 which drive the pulley 24. Pulley 24, by means of the turning belt 25 which encircles the main hub 13, may rotate the carriage 17, the four bellows, the fuselage 22 and all associated elements, including the turning motors 23 themselves, indefinitely in either direction according to the positions of the rudder pedals, in a manner more fully described hereinafter. The turning motors 23 are of the pneumatic type such as are extremely well known in the art. The sub-frame of the fuselage 22 is designated 27 and it will be seen that this frame is supported by the universal joint which in turn is held by the spindle 14, the universal joint 28, being provided in order that the fuselage 22 may be dived, climbed and banked to the left or right with respect to the stationary base 10. Diving and climbing movements of the fuselage 12 are sometimes hereinafter referred to as "pitching."

It will therefore be appreciated that the fuselage 22 is mounted in a manner to permit indefinite rotation in either direction relative to the stationary base 10 in order that the turning to the left or right of a plane in actual flight may be simulated; and further, that the fuselage may be pitched and banked relative to the stationary

base 10 within the limits of the apparatus, in order to simulate the pitching and banking of a plane in actual flight.

An oval enclosing member 29 is affixed to the rotatable carriage 17 in order to improve the exterior appearance of the training device.

Upon the desk 12 is the recorder 30 which travels over the chart 31 in a direction dependent upon the assumed track of the fuselage 12 and at a speed dependent upon the assumed ground speed of the fuselage, in order that a permanent record of the assumed course of flight of the fuselage 22 may be made. This recorder is well known to the prior art and is completely described in U. S. Patent 2,179,663, issued to Edwin A. Link. Also carried by the desk 12 is the instructor's instrument panel 32 having a plurality of instruments to which the instructor may refer in order to ascertain the assumed air speed, assumed vertical speed, assumed altitude, and other assumed conditions of "flight" of the fuselage 22.

Fuselage banking, pitching and turning valve assembly

Reference is now made to Fig. 3 which is an exploded perspective view of the fuselage pitching, banking and turning control valves.

In Fig. 3 portions of the fuselage sub-frame 27 are shown and it will be seen that the casting 33 is affixed to frame 27 by means of the bolts 34. Integral with casting 33 are the two ears 35 (only one shown), and each of these ears has rotatably mounted therein a stud 36, the axis 38 of studs 36 extending longitudinally of the fuselage 22. The ear 35 and stud 36 shown in Fig. 3 are upon the foremost side of casting 33 as it is oriented within fuselage 22, i. e., toward the head of the fuselage. Each of the studs 36 is affixed in the gimbal ring 37 so that this gimbal ring can pivot about the longitudinal axis 38. The lower end of the control stick 39 in turn is pivotally held by the gimbal ring 37 for movement about the transverse axis 40. It will therefore be appreciated that the control stick 39 may be universally moved with respect to the casting 33. In Fig. 1 it will be seen that the control stick 39 is mounted directly ahead of the student's seat 41 and the instructor's seat is designated 41a.

Still referring to Fig. 3 it will be seen that the member 42 is provided, this member being integral with the lower end of the control stick 39. Integral with the member 42 is the upper portion 43 of the universal joint designated generally by 44a, the lower portion of this universal joint being numbered 45. The lower enlarged portion of member 45 is designated 46, is slotted at 47, and is movably mounted within the hub 48 integral with the circular cap 49 which in turn is integral with the square plate 50. A pin 51 passes through the hub 48 as well as the slot 47 in order to prevent rotation of the hub 48, cap 49 and plate 50. However, portions 45 and 46 of the universal joint are vertically movable with respect to the hub 48.

Still referring to Fig. 3, it will be seen that integral with the lower side of casting 33 are four depending member 52, each of which is internally threaded for the reception of one of the four studs 53. Each of the studs 53 passes through the extensions 54 of the main valve section designated generally by 56 and a nut 57a is placed upon the lower end of each of the studs 53. Accordingly, the main valve section 56 is supported by the casting 33 in fixed relationship at all times.

In the lower portion of Fig. 3 a metal tube 57 having a plurality of holes 58 therein is provided, and affixed upon the lower end of tube 57 is the collar 59 by means of set screw 60. Tube 57 extends through collar 59, the portion of tube 57 below this collar being solid walled, and the upper end of the flexible hose 61 encircles the lower end of tube 57. Tube 61 connects with the conventional turbine 62 seen in Fig. 1. This turbine is mounted upon the rotatable carriage 17 seen in Fig. 2 and provides, as is well known, a source of vacuum.

The collar 59 is vertically adjusted upon the tube 57 so that it supports the rudder valve section designated generally 63 which in turn supports the auxiliary effect valve section designated generally by 64 so that the upper surface of valve section 64 bears against the lower surface of the main valve section 56. The nuts 57a in turn are adjusted so that the upper surface of the main valve section 56 lies against the lower surface of the attitude valve 65.

Tube 57 passes through the close-fitting central openings 66 and 67 of the rudder valve section 63, through the central opening 68 of the auxiliary effect valve section 64, the upper end of tube 57 being integral with the main casting 69 of the main valve section 56.

Referring to Figs. 3 and 3A, the hollow upper end of tube 57 communicates with the chamber 70a formed in casting 69 by the generally circular wall 70 and the bottom 69a of the casting. A plate 71 is fixedly attached to the top of casting 69 by means of the countersunk screws 71a and a central hole 72 is present in the center of plate 71. The bottom 69a of casting 69 is flat and solid with the exception of the ports 73, 74, 75 and 76, 83, 84, 85 and 86, the functions of which will be later described. Integral with the central circular wall 70 of the casting 69 are the radially extending walls 77, 78, 79, 80, 81 and 82. Consequently, the various parts of casting 69 and the plate 71 form the chambers 83a, 84a, 85a, 86a, 74a and 86a. The plate 71 has four openings 89, 90, 91 and 92, each of which opens into one of the respective chambers 83a, 84a, 85a and 86a. Ports 83, 84, 85 and 86 also open into the respective chambers 83a, 84a, 85a and 86a.

The flange 93a, integral with the casting 93 of the attitude valve section 65 is slightly less in diameter than the diameter of plate 71 upon which it rests. Flange 93a is centered, in the neutral position, with respect to plate 71. Integral with casting 93 are the four radial members 94, 95, 96 and 97 which support the hollow central hub 98. The radial members 94, 95, 96 and 97 form four chambers 101a, 102a, 103a and 104a in the attitude valve section 65. A plate 99 is affixed to the top of casting 75 by means of the countersunk screws 99a and this plate is solid except for the central opening 100, the four openings 101, 102, 103 and 104 placed therein, and the four smaller openings 101b, 102b, 103b and 104b. It will be noted that each of the openings 101, 102, 103 and 104 is placed above one of the chambers 101a, 102a, 103a and 104a formed by the radial partitions 94, 95, 96 and 97 and plate 99. The bottom of each of these chambers is open.

In view of the described structure, it will be appreciated that the main central chamber 70a formed in the main valve section 56 by the casting 69 and associated parts is at all times evacuated by the turbine 62 by a predetermined amount less than the prevailing atmospheric pressure. Vacuum flows (to achieve simplicity

of expression vacuum) will be spoken of as a positive rather than a negative phenomenon) through the central port 72 in the plate 71 and through the central port 100 in the attitude valve section 65. The plate 50 rests at all times upon the circular plate 99 affixed to the top of casting 93 and the cup 49 together with plate 50 forms a chamber in which vacuum is present at all times.

When the control stick 39 is in its neutral fore and aft as well as neutral lateral positions, the plate 50 is centered with respect to the plate 99 upon the top of casting 93 of the attitude valve section. In this position the plate 50 covers the main ports 101, 102, 103 and 104 in plate 99, but the four auxiliary ports 101b, 102b, 103b and 104b are not covered by this plate. Accordingly, a limited amount of vacuum is, in the neutral position of stick 39, admitted to the chambers 101a, 102a, 103a and 104a. This same amount of vacuum passes through the ports 89, 90, 91 and 92 of plate 71 into the chambers 83a, 84a, 85a and 86a of the main valve section 56. The vacuum within chamber 83a passes through the port 112 in the side of casting 69, and through the connector 113 and a suitable flexible connection (not shown) to the front pitching bellows 18; the vacuum within chamber 84a passes through the port 114, connector 115 and the flexible hose 116 to the left banking bellows 20; the vacuum within chamber 85a passes through the port 117 and a suitable connector and flexible hose (not shown) to the rear pitching bellows 19; while the vacuum within chamber 86a passes through the port 118, connector 119 and flexible hose 120 to the right banking bellows 21.

Accordingly whenever the plate 50 is in its neutral position by virtue of the control stick 39 being placed in its neutral position, an equal amount of vacuum is present in all four of the main bellows 18, 19, 20 and 21, and the fuselage 22 is positioned in the "cruising" position, the fore end of the fuselage being slightly raised, as shown.

However, whenever the student within the fuselage 22 pushes the control stick 39 ahead, to simulate the movement which he would impart to the control stick to cause the nose of the plane to drop, it will be appreciated that the upper end of the control stick 39 would move to the front in Fig. 3, causing the universal joint 44a to move to the rear. Plate 50 similarly moves, to the rear, and it will uncover the port 101 in plate 99 by an amount dependent upon the angular movement of the control stick 39 ahead of its neutral position. At the same time, the plate 50 will uncover the port 103 by an amount dependent upon the same factor. Consequently, an increased amount of vacuum will be applied to the port 101, to the chamber 101a and port 89 to the chamber 83a in the main valve section 56. This increased amount of vacuum will be applied through the port 112, connector 113 and flexible hose to the front pitching bellows 18, causing this bellows to collapse proportionately. At the same time, the movement of plate 50 will cover the port 103b in plate 99 so that vacuum will no longer be applied to the chamber 103a. Instead, the movement of plate 50 will simultaneously uncover the port 103, admitting atmosphere to chamber 103a which is transmitted through the port 91 in plate 71 to the chamber 85a, from whence it passes through the port 117, the provided connector and flexible hose to the rear pitching bellows 19. This bellows will conse-

quently be expanded accordingly. Hence the contraction of bellows 18 and expansion of bellows 19 as a result of a forward movement of the upper end of control stick 39 will result in a lowering of the nose of the fuselage 22.

On the other hand should the control stick 39 be moved to the rear, it will be appreciated that the plate 50 moves ahead in Fig. 3, opening the port 103 in plate 99 and admitting an increased amount of vacuum through the previously described chambers to the port 117 which connects with the rear pitching bellows 19. At the same time the port 101b is covered and port 101 is uncovered. Accordingly, atmosphere is admitted through the port 101 and the intermediate ports and chambers to the connector 113 which connects with the front pitching bellows 18. Accordingly, bellows 18 is expanded while bellows 19 is contracted, and the nose of fuselage 22 is raised.

It will therefore be appreciated that the pitching attitude of the fuselage 22 may be controlled by the student in the trainer to place the fuselage in any pitching attitude, within the limitations of the apparatus, by fore and aft movement of the control stick 39.

It should be noted that whenever the control stick 39 is moved directly fore or aft, the plate 50 does not cover either of the ports 102b or 104b or uncover either of the ports 102 or 104, and accordingly the lateral banking position of fuselage 22 is unaffected.

Assuming that the student moves the upper end of control stick 39 to the left of its neutral lateral position, it will be appreciated that the plate 50 is moved to the right of the fuselage, thereby uncovering the port 102 in plate 99 by an amount dependent upon the angular displacement of the control stick 39. An increased amount of vacuum will therefore be passed through the port 102 and the port 90 in plate 71 of the main valve section 56. This increased vacuum will manifest itself within chamber 84a and will pass through the port 114, connector 115 and the flexible connector 116 to the left banking bellows 20, causing this bellows to contract proportionately. Simultaneously therewith, the plate 50 will cover the auxiliary port 104b in plate 99, preventing the application of vacuum to the chamber 104a in the attitude valve section 63, but at the same time the movement of plate 50 will uncover the port 104 proportionately and atmosphere will enter the chamber 104a through this port and will enter the chamber 86a through the port 92 in plate 71. Atmosphere then passes through the port 118 in casting 68 of the main valve section as well as through the intermediate connector 119 and flexible connection 120 to the right banking bellows 21. Accordingly, when the control stick 39 is moved to the left the left banking bellows 20 is collapsed proportionately and the right banking bellows 21 is expanded proportionately, causing the fuselage 22 to bank to the left.

If on the other hand, the student moves the upper end of control stick 39 to the right, the plate 50 moves toward the left side of the fuselage covering the port 102b and opening the port 102 to the atmosphere. Atmosphere passes through the port 90 into chamber 84a and thence through the port 114, connector 115 and connector 116 to the left banking bellows 20. Simultaneously therewith the movement of the plate 50 opens port 104 and vacuum passes through this port and port 92 to the chamber 86a in the main

valve section 56. This increased vacuum passes through the port 118 and intermediate connecting elements to the right banking bellows 21. Accordingly left banking bellows 20 is expanded by the atmosphere admitted thereto and right banking bellows 21 is collapsed by the increased amount of vacuum applied thereto, resulting in a banking of fuselage 22 to the right.

Again, it should be particularly noted that whenever the control stick 39 is moved directly to the left or right, the movement of plate 50 does not affect in any manner the ports 101, 101b, 103 or 103b, and consequently the pitching attitude of fuselage 22 is not affected.

Without a detailed explanation it should be understood that whenever the control stick 39 is moved ahead or to the rear of its neutral fore and aft position and is simultaneously displaced to the right or left of its neutral lateral position, the plate 50 will properly be moved relative to the plate 99 so that the main ports 101, 102, 103, 104 and the auxiliary ports 101b, 102b, 103b and 104b are covered or uncovered to properly place the fuselage 22 in a combined pitching and banking position, simulating the position in which a real airplane would be placed were its control stick moved accordingly.

Reference is now made to Fig. 3 where the rudder valve section 63 is seen to comprise a top 127 integral with the depending vertical cylindrical wall 128 which is of lesser diameter than the top 127, forming the flange 129. The top 127 is flat and solid with the exception of the ports 130, 131, 132, 133 and 134, and the channel 135. Integral with the top 127 and the cylindrical wall 128 is the vertical, cylindrically shaped wall 136 which is slightly larger in diameter than the hole 67 in the top 127 and which extends around the hole 67, except for the provision of the two vertical walls 137 and two vertical walls 138. An interior flange 139 is integral with the lower edges of the vertical walls 136 in order to form the hole 66, and integral with the flange 139 is the extension 140 which merges with the vertical side wall 128. The vertical members 137 extend from the cylindrical wall 136 to the outer cylindrical wall 128.

The outer wall of channel 135 depends vertically from the outer edge of flange 129 and is designated 141, it has two curved vertical end walls 142 integral with the outer wall while its inner wall is formed by the vertical cylindrical wall 136 which is integral with the end walls. The bottom of channel 141 is solid and designated 143, this bottom being integral with the walls of the chamber. The vertical walls 138 are integral with the top 127 and with the cylindrical wall 128, as well as with the inner cylindrical wall 136, a notch 144 being cut in the inner cylindrical wall 136 so as to form a duct leading from within cylinder 136 to the channel 135. Integrally formed with the walls 138 and with the cylinder 136 is a suitable bottom (not shown) so as to render the passage from cylinder 136 to channel 135 airtight. A notch 145 is cut in the top of plate 127 so as to extend the top of channel 135 back toward the hole 67.

Inasmuch as tube 57 is inserted through the hole 66 and hole 67 in the rudder valve section 63, it will be appreciated that vacuum leaks through the holes 58 in tube 57 at all times so as to be present within cylinder 136. This vacuum is also present at all times within the

port 131 which is in the top 127 between the vertical walls 137, and is at all times present within the channel 135 and notch 145 in the top 127. At the same time atmosphere is always present within the ports 130, 132, 133 and 134.

Turning now to a detailed description of the auxiliary effect valve section 64, as shown in Figs. 3 and 3b, it will be recalled that this valve section has a central hole 68 which extends completely therethrough for the reception of the metal shaft 57.

It will be noted that the leaf 64 has three arcuate slots 146, 147 and 148 extending completely therethrough, these slots being located and separated as shown. Also placed in the top surface of section 64 are the two counterbores 149 and 150, these counterbores extending only a portion of the way through the section 64, with the exception of the circular ports 151 and 152 which extend completely through section 64.

In the lower surface of leaf 64 are the two arcuate counterbores 153 and 154 which extend upwardly part way through the section 64 and communicate with the arcuate counterbore 155 placed in the top of section 64 by means of the two counterbores 156 and 157. Counterbores 155, 156 and 157 do not extend completely through leaf 64.

When the lower surface of the auxiliary effect valve section 64 lies against the upper surface of the rudder valve section 63, and the two sections are in their neutral operative positions, the vacuum-filled port 131 of section 63 lies between the two ports 151 and 152 of the section 64 and slightly overlaps these two ports so that a limited amount of vacuum is introduced into the counterbores 149 and 150 in the upper surface of section 64. At the same time the port 73 in the lower surface of the main valve section 56 is directly above the middle portion of counterbore 149 and port 74 is directly above the center portion of counterbore 150. In the central positions the atmosphere ports 130 and 132 are slightly displaced from the lower ends of the ports 151 and 152 which extend completely through the section 64.

Accordingly, when the sections 63, 64 and 56 are in their neutral operative positions, a limited amount of vacuum passes from the vacuum port 131 through the ports 151 and 152 and counterbores 149 and 150 through the ports 73 and 74 into the chambers 73a and 74a, and thence through the ports 75 and 76, the connectors 158 and 159 and flexible tubings 160 and 161 to the turning motors 23. Accordingly an equal amount of vacuum is introduced to the turning motors through the lines 160 and 161 and these motors do not operate to rotate the fuselage 22.

In Fig. 3 it will be seen that the cable 162 encircles the section 63, as shown, and is fastened thereto by suitable means to prevent slippage, this cable also running upon the pulleys 164 and having its forward left and right ends selectively connected to the left and right rudder pedals 26. Whenever the rudder valve section 63 is rotated clockwise in response to a pressing forward of the right rudder pedal, it will be appreciated that the vacuum port 131 in section 63 will move out of engagement with the port 152 in the section 64 and that the atmosphere port 132 will register with the port 152. Accordingly, atmosphere will pass through the ports 132, 152, and counterbore 150 to the port 74 and chamber 74a in the main valve section 56. Atmosphere then passes from chamber 74a through the port

76, connector 159, and flexible hose 161 to the turning motors 23. At the same time the vacuum port 131 will overlap the port 151 in section 64 to an increasing extent, and an increased amount of vacuum will be passed through port 151, counterbore 149, and port 73 in the main valve section 56 to the chamber 73a, from which it passes to the turning motors through the port 75, connector 158, and flexible hose 160. The increased amount of vacuum passing through the flexible hose 160 and the passing of atmosphere through the flexible hose 161 to the turning motors results in an operation of these motors such as to turn the fuselage 22 to the right.

On the other hand, assuming that the rudder valve section 63 is rotated counterclockwise from its neutral position in response to a pressing forward of the left rudder pedal, the vacuum port 131 in section 63 will move away from the port 151 in section 64 and will come into an increasingly overlapping position with respect to the port 152 in section 64. Accordingly, more vacuum will be introduced into the chamber 73a and to the turning motors 22 through the port 76, connector 159 and flexible hose 161. Simultaneously therewith, the vacuum port 131 will move out of engagement with the port 151 and the atmosphere port 130 will move into engagement with port 151, whereupon atmosphere will be introduced to the chamber 73a and to the turning motors 23 through the port 75, connector 158 and hose 160. The introduction of atmosphere to the turning motors 23 through the flexible hose 160 and the introduction of vacuum to turning motors through the hose 161 in response to a counterclockwise rotation of the rudder valve section 63, caused by a pressing forward of the left rudder pedal, will result in a rotation of the fuselage 22 to the left.

It will be appreciated that the rate of rotation of fuselage 22 will depend upon the angular displacement of the rudder valve section 63 from its neutral position, this displacement in turn being in accordance with the magnitude of the displacement of the rudder pedals 26 from their neutral position.

As is well known to those skilled in the art, whenever a plane in actual flight is turned in either direction the plane automatically banks in the direction of the turn. The previously described valve arrangement is such that whenever the fuselage 22 is turned in either direction, vacuum and atmosphere are introduced into the banking bellows 20 and 21 to automatically cause the fuselage 22 to bank in the direction of the turn.

When the two valve sections 63 and 64 are in their neutral operative positions, the port 133 in section 63 lies immediately below and between the adjacent ends of the two counterbores 146 and 147 which extend completely through section 64, and the atmosphere port 134 is similarly positioned with respect to the adjacent ends of the counterbores 147 and 148. Also the vacuum filled counterbore 135 in section 63 is below and slightly offset from the clockwise end of counterbore 146 and the counterclockwise end of counterbore 148 in section 64. Also, when section 64 is neutrally positioned, the port 84 in section 56 lies immediately above the center of counterbore 146 and port 86 in section 56 lies immediately above counterbore 148.

Consequently, when the rudder valve section 63 is rotated clockwise in response to a pressing forward of the right rudder pedal—which movement results in a rotation of the fuselage 22 to the

right—the atmosphere port 133 overlaps the counterbore 146 and atmosphere passes through port 133, centerbore 149 and port 84 into the chamber 86a in the main valve section 56. It has previously been explained that this chamber is connected to the left banking bellows 20, and so atmosphere will be admitted to this bellows resulting in an expansion thereof. Simultaneously, the clockwise rotation of rudder valve section 63 will result in the clockwise end of the vacuum filled centerbore 135 overlapping the counter-clockwise end of the counterbore 148 in the section 64. Vacuum will pass through counterbore 148 and the port 86 into the chamber 86a in the main valve section 56. It has previously been explained that this chamber is connected to the right banking bellows 21, and so vacuum will be introduced into that bellows, resulting in a contraction thereof. The expansion of the left banking bellows 20 and simultaneous contraction of the right banking bellows 21 will result in a banking of fuselage 22 toward the right. The turning of the fuselage to the right also results in a banking to the right.

On the other hand, should the rudder valve section 63 be rotated counterclockwise in response to a pressing forward of the left rudder pedal—which movement results in a rotation of the fuselage 22 to the left—the atmosphere port 134 will come into an overlapping position with respect to the clockwise end of counterbore 148 in the section 64, and atmosphere will be fed through this counterbore and the port 86 into the chamber 86a in the main valve section 56. From this chamber the atmosphere will be introduced into the right banking bellows 21. Simultaneously therewith the counterclockwise end of the vacuum filled counterbore 135 will overlap the clockwise end of counterbore 146 and vacuum will pass through this counterbore and the port 84 into the chamber 86a in the main valve section. Vacuum will pass from this chamber into the left banking bellows 20. The introduction of vacuum into the left banking bellows 20 and the introduction of atmosphere into the right banking bellows 21 will result in a banking of the fuselage 22 to the left. Consequently, whenever the fuselage 22 is turned to the left it also banks to the left.

It has been explained that the rate of rotation of the fuselage 22 depends upon the angular displacement of the rudder valve section 63 from its neutral position. At the same time it will be appreciated that the banking movement imparted to the fuselage 22 by a rotation of the rudder valve section 63 will also be proportional to the angular displacement of the rudder valve section from its neutral position. Therefore the fuselage 22 not only properly banks in the direction of the turn, but the angle of the bank is proportional to the rate of turning, accurately simulating the banking of a plane in actual flight caused by the turning thereof.

Referring again to the case of a plane in actual flight for purposes of comparison, whenever the plane is turning the nose of the plane tends to drop. This is commonly referred to in the art as "automatic nose down with turn." The previously described valve arrangement also operates to lower the nose of the fuselage 22 whenever it is turning.

Referring to Fig. 3, the counterbore 135 and notch 145 are always filled with vacuum, and when the valve sections are in their neutral operative positions, the notch 145 lies immediately below and slightly off-set from the adjacent ends of the

counterbores 153 and 154 placed in the lower surface of section 64, and the port 83 in section 56 lies immediately above the center of counterbore 155 which is connected with counterbores 153 and 154. Also the atmosphere ports 133 and 134 lie below and are slightly off-set from the ends of counterbore 147 which passes through section 64, while port 85 in section 56 lies immediately above the center of counterbore 147. Whenever valve section 63 is moved in either direction from its neutral position, one of the ports 133 and 134 will come into overlapping relation with the counterbore 147 in section 64. Atmosphere will pass through counterbore 147 and port 85 into the chamber 85a in the main valve section 56. It has been previously shown that this chamber is connected to the rear banking bellows 19, and accordingly atmosphere will be introduced into that bellows. Simultaneously therewith whenever the rudder valve section 64 is rotated in either direction from its neutral position, the vacuum filled notch 145 will come into overlapping position with one of the counterbores 153 and 154 placed in the bottom of the auxiliary effect of section 64. Accordingly vacuum will pass from the counterbore in question along the counterbore 156 or 157 into the counterbore 155 which engages the port 83 in the bottom of section 56. Vacuum will be introduced into the chamber 83a, and inasmuch as this chamber is connected to the front pitching bellows 18, vacuum will be introduced into that bellows. The simultaneous introduction of the vacuum into the front pitching bellows 18 and atmosphere into the rear pitching bellows 19 will result in a lowering of the nose of fuselage 22.

Accordingly the valve arrangement disclosed herein is such that the nose of the fuselage 22 is lowered whenever the fuselage 22 is turning to the left or right.

Also in the case of a plane in actual flight whenever the plane is banked to the left or right, the plane automatically turns in the direction of the bank. The previously described valve arrangement, together with the apparatus now to be described, operates to cause the fuselage 22 to automatically turn in the direction of the bank when the fuselage is banked.

Referring now to Fig. 4, the main spindle 14 and the main universal joint 28 are shown as well as the sub-frame members 27 of the fuselage 22. The sub-frame members 27 are affixed by means of bolts 172 to the plate 170 which is directly above the universal joint 28. The ears 173 which form a part of the universal joint 28 are integral with the plate 170 and the gimbal ring 174 is pivotally mounted within the ears 173 for pivoting about the axis 175 which extends longitudinally of the fuselage 22. Affixed to the rear ear 173 is the integral extension 176, upon the outer end of which is pivotally mounted the bell crank 177, the fore end of which is pivotally attached to the link 178. The gimbal ring 174 is pivotally mounted in the upper end of the main spindle 14 for pivoting about the transverse axis 179 and the lower end of member 178 is pivotally attached to the stud 180, at a point on the transverse axis 179. The lower end of crank 177 has pivotally attached thereto the rear end of link 180a, the forward end of which is pivotally attached to the auxiliary effect valve section 64 by means of the pin 181, seen in Fig. 3.

In Fig. 4 it will be appreciated that whenever the fuselage 22 is banked toward the left, the

ears 173 integral with plate 170 are rotated counterclockwise as seen from the rear of the trainer. The right end of stud 176 will move upwardly and inasmuch as the lower end of link 178 does not move, bell crank 177 will also pivot upon stud 176 and the lower arm of bell crank 177 will move towards the rear pulling link 180a in the same direction and causing the auxiliary effect valve section 64 to be rotated clockwise as seen from above.

Referring now to Fig. 3, and assuming that before the banking to the left of fuselage 22 occurred the valve sections were in their neutral positions, the clockwise rotation of the auxiliary effect valve section 64 will cause the port 152 to overlap the vacuum port 131 in the rudder valve section 63 by a greater amount dependent upon the angle of bank. Accordingly, increased vacuum will be passed through the port 152, counterbore 149 and the port 74 in the main valve section 56 into the chamber 74a, and through the port 76, connector 159 and flexible connection 161 to the turning motors 23. Simultaneously therewith, the clockwise rotation of the section 64 will cause the port 151 in section 64 to overlap the atmosphere port 130 by a proportionate amount and the correct amount of atmosphere will be introduced from port 130 through port 151, counterbore 149 and port 73 into the chamber 73a in the main valve section 56. From this chamber the atmosphere passes through port 75, connector 158 and the flexible hose 160 to the turning motors 23.

It has previously been shown that a passing of vacuum through the flexible hose 161 to the turning motors and a passage of atmosphere through the flexible connection 160 results in a rotation of the trainer fuselage 22 to the left.

Accordingly, whenever fuselage 22 is banked toward the left, it automatically turns to the left, and it will be appreciated that the rate of automatic turning will be dependent upon the angle of bank.

On the other hand, referring to Fig. 4, when the fuselage 22 is banked toward the right it will be appreciated that the central pivot of bell crank 177 moves downwardly and that the link 180a is moved toward the head of the fuselage, resulting in a counterclockwise rotation of the auxiliary effect valve section 64, as seen from above.

Referring to Fig. 3, and assuming that before the banking to the right of fuselage 22 occurred the valve sections were in their neutral position, it will be appreciated that the counterclockwise rotation of the auxiliary effect valve section will cause the port 151 in section 64 to overlap the vacuum port 131 to a greater extent. Accordingly, increased vacuum will be introduced through the port 131, port 151, counterbore 149 and port 73 to the chamber 73a, from whence it passes through the port 75, connector 158 and flexible hose 160 to the turning motors 23. Simultaneously therewith, the port 152 in section 64 will overlap the atmosphere port 132 in the rudder valve section 63 and atmosphere will pass through port 132, port 152, counterbore 150, and port 74 into the chamber 74a, and from that chamber it passes through the port 76, connector 159, and flexible connection 161 to the turning motors. It has previously been stated that a passage of atmosphere to the turning motors through the hose 161 accompanied by a passage of vacuum to the turning motors through the hose 160 results in a rotation of

the fuselage 22 toward the right. It will therefore be appreciated that whenever the fuselage 22 is banked to the right, it is automatically turned to the right and, of course, the rate of automatic turning caused by the banking of the fuselage depends upon the angle of bank of the fuselage.

One of the stated objects of this invention was to provide a novel main valve system for use in grounded aviation trainers whereby the valve arrangement could be made responsive to the assumed factor of air speed so that the pitch attitude of the fuselage would be dependent upon the assumed air speed. In the case of a plane in actual flight, it is well understood by those skilled in the art that an increase in air speed automatically results in a raising of the nose of the plane while a decrease in air speed has the opposite effect.

Referring now to Fig. 5, there is shown in block form a unit 182 labeled "Air speed output." The output shaft of this unit is designated 183. For the purposes of this disclosure, it is not deemed necessary to disclose in detail the factors which are introduced into the air speed output unit 182 in order that the output shaft 183 will always be positioned from a predetermined zero point according to the instant assumed air speed of the fuselage. However, for a detailed disclosure thereof, reference may be made to the copending application Serial No. 619,361 filed upon September 29, 1945, in the name of Karl A. Kail for "Aviation trainer," or to the application Serial No. 634,492 filed December 12, 1945, in the names of Stanley L. Hayes and Milton S. Wade. Also, those skilled in the art will readily appreciate that the factors which are introduced into the air speed output unit 182 may be the factors of throttle lever setting and pitch attitude of the fuselage, as disclosed in U. S. Patent 2,099,857 issued to Edwin A. Link.

It is sufficient to bear in mind that the shaft 183 is always rotated from a predetermined neutral position through an angle dependent upon the instant assumed air speed, and accordingly the gear 184 affixed upon the outer end of shaft 183 as well as the gear 185 driven by gear 184 are always similarly positioned. Gear 185 is affixed upon the outer end of the screw 186 which travels in the nut 187 affixed upon the upper surface of the plate 99 of the attitude valve section 65. Suitable means is provided to prevent longitudinal movement of screw 186.

As assumed air speed increases, the air speed output unit 182 is operated in such a manner that the screw 186 moves the nut 187 and disc 99 moves toward the rear of fuselage 22.

Referring to Fig. 3, it will be appreciated that whenever the plate 99 moves to the rear, plate 50 remaining stationary, the port 103 in plate 99 moves out from under plate 50 and vacuum passes through this port into the chambers 103a and 85a and through the port 117 to the rear pitching bellows 19. Simultaneously therewith, the movement to the rear of plate 99 causes the auxiliary port 101b to be covered by the plate 50 and the port 101 moves out from under plate 50 so that atmosphere passes through this port into the chamber 101a and chamber 83a, and then through the port 112, connector 113 and intermediate elements to the front pitching bellows 18. The admission of vacuum to the rear pitching bellows 19 and simultaneous admission of atmosphere to the front pitching bellows 18 results in a raising of the nose of the fuselage.

Of course this raising of the nose of the fuselage may be checked if desired by a forward movement of the control stick 39.

On the other hand, should the factor of assumed air speed be decreased, the operation of unit 182 in Fig. 5 will be reversed so as to move the disc 99 toward the head of the trainer an amount dependent upon the assumed decrease. Referring to Fig. 3 it will be appreciated that when disc 99 moves toward the head of the trainer, port 103b is covered and port 103 is opened to the atmosphere, admitting atmosphere to the rear pitching bellows 19 in the manner previously described. Simultaneous therewith, the port 101 will be opened to the vacuum within cap 49 and vacuum will be admitted to the front pitching bellows 18.

The consequent collapsing of the front bellows 18 and expansion of the rear bellows 19 will result in a lowering of the nose of the fuselage. Accordingly, the improved valve structure of my invention is adapted for use to affect the attitude of the fuselage according to the instant assumed air speed.

In view of the preceding disclosure it will be appreciated that the objects of this invention, as stated in the introduction hereof, have been met.

It will be appreciated by those skilled in the art that many changes may be made in the disclosed embodiment of my invention without departing from the substance thereof. Also, those skilled in the art will appreciate that a control column may be substituted for the control stick shown herein. All such changes are intended to be covered by the following claims.

I claim:

1. In a grounded aviation trainer of the type comprising a fuselage universally mounted with respect to a stationary base and four expandible-contractible bellows connected to said fuselage for pivoting the same, a valve comprising a flat surface, two pairs of ports in said flat surface, the ports of each pair being located on opposite sides of the center of said flat surface and a pneumatic connection between each port and a different one of said bellows, a plate arranged to substantially cover all of said ports when the plate is neutrally positioned, a vacuum chamber formed in the center of said plate, a manually controllable member, and a connection between said manually controllable member and said plate arranged to move said plate in any direction radially of said flat surface dependent upon the direction of movement of said manually controllable member, whereupon said ports are selectively opened into said vacuum chamber and vented to the atmosphere.

2. In a grounded aviation trainer of the type comprising a fuselage universally mounted with respect to a stationary base and four collapsible-expansible bellows connected to said fuselage for pivoting the same, a valve assembly comprising a valve section having four circumferentially spaced and separate chambers, a pneumatic connection between each of said chambers and a different one of said bellows, a flat surface and four ports in said flat surface, one of each of said ports being in communication with a different one of said chambers, a plate having a vacuum chamber therein arranged to lie upon said flat surface so as to substantially cover each of said ports when the plate is in its neutral position, a manually movable control, and a connection between said manually movable control and said valve assem-

bly for changing the relative positions of said plate and ports according to the direction of movement of the manual control, whereupon said ports are selectively opened into said vacuum chamber and to the atmosphere.

3. In a grounded aviation trainer of the type comprising a fuselage universally and rotatably mounted with respect to a stationary base for pitching, banking and turning movements, a pneumatically operated turning motor for rotating the fuselage and four bellows for pitching and banking the fuselage, the combination of a valve assembly including a first valve section having six separate circumferentially arranged chambers, a pneumatic connection between each of four of said chambers and a different one of said bellows and a pneumatic connection between each of the other two of said chambers and said turning motor, a port opening into each of said first four chambers through the top thereof and a port opening into each of the other two chambers through the bottom thereof, a second valve section placed below said previously mentioned section and having a vacuum chamber and a port leading therefrom as well as at least one atmosphere port, a plate having a vacuum chamber placed above the first four ports, said plate being arranged to substantially cover the said four ports in the top of said first valve section when the plate is neutrally positioned, a first manual control in the trainer connected to said plate for moving the same to selectively open said four ports into the vacuum chamber in said plate and to the atmosphere according to the direction of movement of the manual control, and a second manual control in the trainer connected to said second valve section for selectively causing the vacuum port and atmosphere port therein to register with the said two ports in the bottom of the first section.

4. In a grounded aviation trainer of the type comprising a fuselage pivotally mounted with respect to a stationary base and a pair of expandible-contractible bellows connected to said fuselage for pivoting the same, a valve assembly comprising a flat surface, a pair of ports in said flat surface, a connection between one of said ports and one of said bellows and a connection between the other of said ports and the other of said bellows, a plate arranged to substantially cover both of said ports when said plate and said flat surface are neutrally positioned one with respect to the other, a vacuum chamber, a manually controllable member, a movable member forming a part of said trainer, a means forming a part of said trainer for positioning said movable member in accordance with the instant assumed air speed of said trainer, means interconnecting said manually controllable member and said valve assembly for changing the relative positions of said flat surface and said plate and means interconnecting said valve assembly and said movable member for changing the relative positions of said flat surface and said plate, whereupon said ports are selectively opened into said vacuum chamber and the atmosphere according to the combined positions of said manually controllable member and the instant assumed air speed.

5. In a grounded aviation trainer of the type comprising a fuselage universally mounted with respect to a stationary base and four expandible-contractible bellows connected to said fuselage for pivoting the same, a valve comprising a flat surface, two pairs of ports in said flat surface, and a pneumatic connection between each port

and a different one of said bellows, a plate arranged to substantially cover all of said ports when the plate is neutrally positioned, a vacuum chamber formed in said plate, a manually controllable member, and a connection between said manually controllable member and said plate arranged to move said plate in any direction radially of said flat surface dependent upon the direction of movement of said manually controllable member, whereupon said ports are selectively opened into said vacuum chamber and vented to the atmosphere.

6. In a grounded aviation trainer of the type comprising a fuselage universally and rotatably mounted with respect to a stationary base for 15 pitching, banking and turning movements, a pneumatically operated turning motor for rotating the fuselage and four bellows for pitching and banking the fuselage, the combination of a valve assembly including a first valve section having six separate circumferentially arranged pneumatic passages, a pneumatic connection between each of four of said passages and a different one of said bellows and a pneumatic connection between each of the other two of said passages and said turning motor, a second valve section placed below said previously mentioned section and having a vacuum passage and an atmosphere passage, a plate having a vacuum chamber placed above the first valve section, said plate being 20 arranged to substantially cover the said four passages in the top of said first valve section when the plate is neutrally positioned, a first manual control in the trainer connected to said plate for moving the same to selectively open said four passages into the vacuum chamber in 25 said plate and to the atmosphere according to the direction of movement of the manual control, and a second manual control in the trainer connected to said second valve section for selectively causing the vacuum passage and atmosphere 30 passage therein to register with the said two other passages in the said first section.

7. In a grounded aviation trainer of the type comprising a fuselage universally and rotatably 40 mounted with respect to a stationary base for 45 pitching, banking and turning movements, a

pneumatically operated turning motor for rotating the fuselage, four pneumatically operated bellows for pitching and banking the fuselage, one of a plurality of separate pneumatic lines connected to each of said bellows and a pair of pneumatic lines connected to said turning motor, valve means for controlling the pneumatic pressure in each of said pneumatic lines, said valve means including a distributing member having a flat surface and six pneumatic passages therein each of which passes through said flat surface and is in communication with a different one of said pneumatic lines, a first movable valve section having two flat surfaces one of which is placed against the flat surface of the distributing member and a plurality of pneumatic passages therethrough, a second movable valve section having a flat surface placed against the other flat surface of the first valve section and a plurality of pneumatic passages therein, a source of vacuum connected to certain of the pneumatic passages in said second valve section and certain of the pneumatic passages in said second valve section being vented to the atmosphere, and manually operable means in the fuesalge connected to each of the movable valve sections for selectively operating the same to regulate the passage of vacuum and atmosphere from the second movable valve section through the first movable valve section to the said distributing member and pneumatic lines.
